BOTTOM LEVEL TANK SAMPLER

Murray D. Cannell, Wilmington, Calif.

Application March 29, 1952, Serial No. 279,299

4 Claims. (Cl. 73—425.4)

1

This invention relates to a tank sampler in which a fluid sample can be taken from the exact bottom of a tank to permit the user to determine the presence of water or other extraneous material in the bottom of a tank.

My invention is adapted to be used on railway tank cars which are loaded with petroleum products, also drum type containers, tank trucks, small storage tanks, etc., and the prime purpose is to determine if water is present in the bottom of these various containers.

An object of my invention is to provide a novel bottom level tank sampler which is mounted on the lower end of a tube, which can be inserted into the tank or other container. This sampler is so constructed that it will take a sample only from the exact bottom of the tank or container.

Another object of my invention is to provide a novel tank sampler of the character stated which is moved to either open or closed position by exerting pressure or relieving pressure upon the tube which mounts the tank sampler.

A feature of my invention is to provide a novel tank sampler which will take a sample from the exact bottom of a tank or container, and which can be used to dispose this sample in a small necked bottle or glass container usually used to store these samples.

Still another object of my invention is to provide a novel tank sampler of the character stated, which is simple in construction, inexpensive to manufacture, and will not create a spark in the tank or container, and further, which is small and compact so that it can be easily handled by the user.

Other objects, advantages and features of invention may appear from the accompanying drawing, the subjoined detailed description and the appended claims.

In the drawing:

Figure 1 is a side elevation of my tank sampler mounted on a tube.

Figure 2 is a bottom plan view of the tank sampler.

Figure 3 is a fragmentary longitudinal sectional view of the sampler in loaded or closed position.

Figure 4 is a view similar to Figure 3 but showing the sampler in open position to either charge or discharge.

Referring more particularly to the drawing, the numeral 1 indicates a tank, or container, and the numeral 2 the exact bottom of that tank. The tank, or container, may be filled with a petroleum product and there is usually a quantity of water

2

below the petroleum product, and it is desirable and necessary to determine if such a water layer is present, and also the approximate amount of such water.

To determine these facts, I provide a long tube 3, preferably formed of a non-magnetic and, therefore, spark proof material. The tube 3 can be either rigid or flexible, and is of sufficient length to extend diametrically through the tank, or container, and through the access port, which is usual in tank cars, or containers, or the like. A sampler 4 is mounted on the lower end of the tube 3 and such sampler consists of a body 5 which is provided with thread 6 at the upper end 10 which screw into the bottom of the tube 3. A tubular member 7 is slidably mounted in the bore 8 of the body 5. This tubular member includes an integral head 9 at the lower end and the head is formed with a transverse groove 10. A drilled passage, or duct, 11, extends vertically through the tubular member 7 and the lower end of this duct opens into the groove 10 substantially as shown. A transverse port 12 adjacent the upper end of the tubular member 7 also opens into the duct 11, and serves as an ingress and egress port for the fluid, as will be further described.

A counterbore 13 in the body 5 extends upwardly from the bottom of the body and accommodates a spring 14, which bears against the top of the head 9 and urges the tubular member 7 downwardly to its closed position. A disc valve 15 is mounted on the upper end of the tubular member 7 and is secured in position by the nut 16 which screws onto the top of the tube and against the valve. The spring 14 thus presses the valve 15 against the top of the body 5, and in this position the port 12 is below the top of the body 5, thereby closing the duct 11 and preventing any fluid from moving into or out of the tube 3.

By exerting pressure on the tube 3, the head 9 is pushed upwardly into the body 5 against the tension of the spring 14, thus moving the port 12 above the top of the body 5 and permitting fluid to flow into or out of the tube 3. This position is shown in Figure 4. It will also be noted that the head 9 can be placed flat against the bottom 2 of the tank, or container, and fluid will still flow into the duct 11, due to the transverse groove 10. This will be evident from Figure 1. By merely releasing downward pressure on the tube 3, the spring 14 will close the valve 15, thus trapping fluid in the tube 3 until the tube is withdrawn from the tank or container. Then to release the sample from the tube 3 it is only necessary to again insert the head 9 into the narrow neck of a

sample bottle and by pushing downwardly on the tube 3 the valve 15 is again opened and fluid flows through the ports 12 and the duct 11 and thence into the sample bottle.

The head 9 is limited in its upper movement into the body 5 by engagement with a shoulder 17 in the body 5. The downward movement of the head 9 is, of course, limited by engagement of the valve disc 15 against the top of the body 5.

Having described my invention, I claim:

1. A tank sampler comprising a body, a tube, means securing the body to one end of said tube, a tubular member slidably mounted in said body, said tubular member having a duct extending longitudinally therethrough, a valve on the upper end of the tubular member seating on the top of the body, said duct extending from below the valve to the bottom of the tubular member, and spring means engaging the tubular member and the body and pressing the tubular member downwardly to seat said valve.

2. A tank sampler comprising a body, a tube, means securing the body to one end of said tube, a tubular member slidably mounted in said body, said tubular member having a duct extending longitudinally therethrough and a transverse groove in its bottom into which the duct extends, a valve on the upper end of the tubular member seating on the top of the body, said duct extending from below the valve to the bottom of the tubular member, and spring means engaging the tubular member and the body and pressing the tubular member downwardly to seat said valve.

3. A tank sampler comprising a body, a tube,

5 10 15 20 25

means securing the body to one end of said tube, a tubular member vertically slidable in said body, a valve on the upper end of the tubular member seating on the top of the body, said tubular member having a transversely extending port therein below the valve and having a duct extending from the port to the bottom of the tubular member, and spring means engaging the tubular member and the body and pressing the tubular member downwardly to seat said valve.

4. A tank sampler comprising a body, a tube, means securing the body to one end of said tube, a tubular member vertically slidable in said body, a valve on the upper end of the tubular member seating on the top of the body, said tubular member having a transversely extending port therein below the valve and a duct extending from the port to the bottom of the tubular member, and said tubular member having a transverse groove in its bottom, the duct opening into the groove, and a spring positioned in the body, said spring engaging the tubular member and the body to press the tubular member downwardly and seat the valve.
